WRINGER

Robert I. Miner, Salem, Ohio, assignor to Mullins Manufacturing Corporation, Salem, Ohio, a corporation of New York

Application January 11, 1937, Serial No. 119,961

6 Claims. (Cl. 68—263)

The object of my invention is to provide a mechanism by means of which desired pressure relationship between the two rolls may be readily established and disestablished without disturbance of the fundamental setting of the pressure springs, and of such character as to present a neat and effective appearance when the parts are in their normal working relationship.

The accompanying drawings illustrate my invention:

Fig. 1 is a fragmentary elevation, in partial vertical section, of a structure embodying my invention.

Fig. 2 a fragmentary end elevation in partial vertical section,

Fig. 3 a section on line 3—3 of Fig. 1,

Fig. 4 a fragmentary vertical elevation of a modification,

Fig. 5 a fragmentary vertical section showing another modification,

Fig. 6 a section on line 6—6 of Fig. 5, and

Fig. 7 a fragmentary section of another modification.

In the drawings 10 indicates a U-shaped base, preferably formed of sheet metal comprising end uprights 11 and 12 U-shaped in cross section, as indicated in Fig. 3. Within each upright 11 and 12 is a vertical U-shaped guideway 14 adapted to receive and guide the bearing blocks 15 and 16 respectively for the trunnions of the lower roll 17 and upper roll 18. Secured to the inner face of the end wall of upright 12 is a plate 19 provided with spaced ears 20 projected through perforation 21 in said end wall. Pivoted between ears 20 on pin 22 is a link 23, the other end of said link being pivoted on pin 24 carried by ears 25 of a plate 26 secured to the inner face of a hand lever 27 which is U-shaped in cross section, as indicated in Fig. 3. The side walls of lever 27, at its upper end, are projected beyond the middle of the wall (as indicated in Fig. 1) to straddle the hollow bridge wall 28 and these projecting ends are pivoted upon pin 29 carried by the bridge bar 28. In the assembly thus described, the lever 27, link 23, and pivotal connections 24, 22 and 29 form a permanent toggle link connection between the base and one end of the bridge bar.

The outer wall of standard 11 near its upper end carries an outwardly projecting pin 30 over which perforations 31 in one end of bridge bar 28 may be projected. Within bridge bar 28 is a bow spring 35 suspended at its middle, by means of grip 36, upon the lower end of screw 37 threaded in block 38 of bridge bar 28 and pro-

vided with an operating head 39, screw 37 being rotatable relative to spring 35. The opposite ends of spring 35 rest upon the two bearing blocks 16 and adjustment of screw 37 determines the initial pressure of said spring upon the bearing blocks 16 and the upper roll 18.

Secured to the outer face of the end wall of upright 12 is the upper end of a spring 40, the lower end of which is bent to properly coact with a latch 41 anchored at 42 in base 10 and 10 yieldingly urged upwardly by means of a spring 43 surrounding an abutment screw 44 threaded at 45 in base 10 and provided with check nut 46. The parts are so proportioned and arranged that with the right hand end of bridge bar 28 anchored upon pin 30 (Fig. 1) and hand lever 27 depressed to its lowest position, pivot 24 of the toggle will have passed dead center as referred to the pivotal anchorage 22, thereby stressing spring 40 to permit engagement and retention thereof by latch 41, this movement stressing spring 35 upon bearing blocks 16. With the parts in the above described positions, link 23 is prevented from further swinging counterclockwise by engagement with the fastening screws 50 which retain spring 40 in place. For the purpose of quickly releasing the upper roll 18 from the influence of spring 35, I pivot upon channel 14, of upright 12, at 51 a latch release lever 52 which, at its lower end, is notched at 53 to straddle a cam ridge 54 of latch 41. Within upright 11 is pivoted a lever 52' similar to lever 52, notched at its lower end like lever 52, said notch straddling a cam ridge of a plate 41' similar to latch 41 except that the latch tip is omitted and upwardly spring urged by a spring 43'.

The upper end of each of levers 52 and 52' is provided with oppositely extended arms 55, 55', which are projected through perforations in the side walls of the enclosing standards 12 and 11 and these arms are connected by hand engageable plates 56, 56' each of which extends across a face of the structure parallel with the bridge bar, the arrangement being such that when either one of the plates 56 is pushed toward the adjacent uprights, notch 53 acting upon cam ridge 54 will withdraw latch 41 from spring 40 to permit said spring to move the lower end of hand lever 27 outwardly to a point where pivot pin 24 will have been moved clockwise (Fig. 1) to a point 50 slightly beyond the dead center of the toggle link, whereupon spring 35 will be effective to cause continued clockwise movement of link 23 until the entire stress of spring 35 upon bearing block 16 will have been relieved.
